Carl Bauknecht

UNITED STATES PATENT OFFICE.

CARL BAUKNECHT, OF SCHRAMBERG, GERMANY, ASSIGNOR TO HAMBURG-AMERIKANISCHE UHRENFABRIK, OF SCHRAMBERG, GERMANY.

SAVINGS CLOCK.

Application filed February 24, 1927, Serial No. 170,639, and in Germany May 6, 1926.

My invention relates to savings clocks of that type in which the inserted coin is intercepted by a disc which projects in a lateral recess of the coin channel and which, as it rotates slowly, allows the coin to slide down slowly, wherein the latter, so long as it remains in the channel, holds a lever acting upon the locking mechanism of the clock movement in the releasing position and, as soon as it falls out, allows the lever to enter the locking position, if a second coin be not inserted. In known clocks of this type the intersecting disc is provided with recesses adapted to the circular form of the coin for the reception of the latter. In this construction it sometimes happens, particularly if the coin be strongly milled, that the same becomes clamped between the intercepting disc and the locking lever and thus stops the intercepting disc and therefore the whole movement.

In order to avoid this, I provide in combination with the intercepting disc a second spring operated intercepting member, for example in the form of a lever, which likewise projects in the recess of the channel; this member is at first held by the disc in the intercepting position in which the coin lies with only one point of its periphery upon this member, but after the disc has rotated a certain distance the member engages under the spring action in one of the recesses in the disc formed at a deeper angle and releases the coin, whereby the latter likewise comes to lie with only one point of its periphery on the edge of one of the arms formed on the disc by means of recesses, where it remains until this edge in the rotation of the disc moves sufficiently far downwards to allow the coin to drop, while the member is moved back by the next arm of the disc into the intercepting position for receiving a further coin.

In the accompanying drawings Fig. 1 shows the mechanism of a savings clock constructed according to my invention with the locking lever in the releasing position, and Fig. 2 shows the coin channel with the two intercepting members in a different position. To the rear of the coin channel *a* there is fixed a pin *b* on which is pivotally mounted the locking lever *c, d*. The curved and forwardly bent part *e* of the lever arm *c* projects in a lateral recess *f* of the channel *a*. The laterally projecting part *g* of the lever

arm *d* acts upon the locking device of the clock movement. This device is formed by an oscillating member *h* having a resilient hook *i* and being mounted upon the carrier *a¹* of the channel *a*. If there be no coin in the channel, the lever *c, d* allows the oscillating member *h* to take under the action of a spring *k* such a position that the hook *i* projects into the path of a pin *m* fixed to the clock balance *l*, and thus stops the latter. If a coin *n* be inserted it slips between the lever part *e* and the oppositely disposed wall of the channel *a* and thereby brings the lever *c, d* into the releasing position indicated in the drawing, in which the same holds the oscillating member *h* in such a position that the hook *i* allows the balance *l* to swing freely.

The device which intercepts the inserted coin *n* and holds it in the channel *a* for a space of time corresponding to its value consists of a circular disc *o* having four substantially rectangular recesses forming four arms at right angles to each other, which disc is fixed to a toothed wheel *p* that is rotated slowly by a pinion *q* of the clock movement in the direction indicated by the arrow, and projects in a recess *r* provided in the channel *a* opposite to the recess *f*; furthermore the arm *s* of the lever *s, t* which is pivotally mounted at *u* on the front wall of the channel *a* has a rearwardly extending end which projects into the recess *r* and is continuously pressed against one of the arms of the disc *o* by a spring *v* attached to the arm *t*.

When the parts are in the position indicated in Fig. 1, the inserted coin *n* lies with a point of its periphery upon the end of the lever arm *s*. After the disc *o* has rotated a certain distance, the lever *s, t* falls under the action of the spring *v* with the end of its arm *s* into the next recess of the disc, which causes the coin *n* to slip off from this end of the lever and to lie also with a point of its periphery on the corner of one of the arms on the disc as shown in Fig. 2. The coin remains disposed upon this corner until the disc has turned through an angle of 90°, that is to say until it has again reached the position indicated in Fig. 1, but with the next arm engaged in the recess *r*, and its corner referred to has moved downwardly such a distance that the coin may drop. The lever *s, t* has in the meantime been reversed

by this arm of the disc *o* into the position indicated in Fig. 1, so that if a further coin be in the channel *a* the lever can intercept it. If there be no further coin in the channel the locking lever *c*, *d* swings back, as the first coin *n* drops, and with it also the oscillating member *h*, the hook *i* again arresting the balance *l* so that the clock stops.

What I claim as my invention and desire to secure by Letters Patent is:

1. In a savings clock, a coin channel, means for engaging the clock movement to prevent the clock from running, means actuated by the weight of a coin for moving said first mentioned means to permit the clock to run, a slowly rotating disc for intercepting a coin in said channel, said disc having angular recesses and arms formed thereby, and a second spring operated member for intercepting a coin, said disc and said member projecting into lateral recesses in said channel, said member at first being held by one of said arms on said disc in position to intercept a coin in said channel, but after said disc has rotated a certain distance being moved by its spring into one of said recesses on said disc to permit the coin to be released and to be intercepted by one of the arms on said disc, said lever on further rotation of said disc being moved back by the next succeeding arm into intercepting position.
2. In a savings clock, a coin channel, means for engaging the clock movement to prevent the clock from running, means actuated by the weight of a coin for moving the first mentioned means to permit the clock to run, a slowly rotating disc for intercepting a coin in said channel, said disc projecting into a lateral recess in said channel and having angular recesses and arms formed thereby, and a spring operated lever for intercepting a coin, said lever being pivotally mounted on said channel and having an end projecting into a second lateral recess in said channel and sliding on the periphery of said disc, said lever at first being held by one of said arms on said disc in position to intercept a coin in said channel, but after said disc has rotated a certain distance being moved by its spring into one of said recesses on said disc to permit the coin to be released and to be intercepted by one of the arms on said disc, said lever on further rotation of said disc being moved back by the next succeeding arm into intercepting position.

In testimony whereof I affix my signature,

CARL BAUKNECHT.
